UNITED STATES PATENT OFFICE.

THEODOR H. J. LECKBAND, OF DES MOINES, IOWA, ASSIGNOR, BY DIRECT AND MESNE ASSIGNMENTS, TO ALFRED C. EINSTEIN, OF ST. LOUIS, MISSOURI.

ACETYLENE-GAS GENERATOR.

SPECIFICATION forming part of Letters Patent No. 718,950, dated January 20, 1903.

Application filed February 2, 1901. Serial No. 45,693. (No model.)

To all whom it may concern:

Be it known that I, THEODOR H. J. LECKBAND, a citizen of the United States, residing at Des Moines, in the county of Polk and State 5 of Iowa, have invented a new and useful Acetylene-Gas Generator, of which the following is a specification.

My object is to provide a gas-generator adapted for storing therein a large quantity 10 of calcium carbid in such position relative to the generator and gas-holder that the reciprocating motions of the bell can be utilized for regulating feed mechanism connected with the magazine, the generator, and the bell, as 15 required to automatically feed carbid to the generator at intervals of time, so that a given quantity of carbid stored in the magazine will be supplied to the generator whenever necessary and such time and labor and personal 20 attention as heretofore required dispensed with.

My invention consists in the construction, arrangement, and combination of parts, as hereinafter set forth, pointed out in my claims, 25 and illustrated in the accompanying drawings, in which—

Figure 1 is a vertical sectional view that shows the relative positions of all the parts and all connected as required for practical 30 use in an acetylene-gas plant. Fig. 2 is a detail view of a portion of the automatic feed mechanism.

The letter A designates the main portion of the gas-holder, adapted to retain water, and 35 A² is the bell, formed and telescopically connected therewith in a common way.

A³ is an auxiliary fixed bottom, by means of which a chamber, adapted to retain water, is produced under said fixed bottom.

40 A⁴ is a safety escape-pipe fixed to the center of the fixed bottom A³ to extend perpendicularly upward and also horizontally outward and then upward.

A⁵ is a tube, open at the bottom and closed 45 at its top, fixed to the center of the top of the bell A² and telescopically connected with the pipe A⁴.

B is a service-pipe, and B² an open-ended supply-pipe, fixed in the bottom A³ and extended up into the bell. 50

B³ is a pipe connected with the pipe B² below the bottom A³ and extending horizontally into a generator.

B⁴ is a rod or pipe fixed to the pipe B³ outside of the main portion of the gas-holder and 55 projecting perpendicularly in alignment with the pipe A⁴. It is obvious the pipe B may be extended to lamps located at a distance. Bearings B⁵ and B⁶ in the form of brackets fixed to the top of the bell A² and connected 60 with the pipes A⁴ and B⁴, in combination with guides c and c', fixed to the top of the part A, aid in retaining the bell perpendicular in its movements.

D is a generator, and D² a magazine adapted 65 for storing carbid therein, fixed on top of the generator. Its lower contracted end is fitted in the top of the generator and terminates in an open-ended elbow D³, to which is fitted a rotatable open-ended feed-cylinder D⁴ to incline downward. Ball-bearing grooves in the overlying parts retain balls f, as required to reduce friction and to facilitate the rotary motion of the feed-cylinder. A plurality of rings f', fixed in the cylinder D⁴, produce 70 annular shoulders that prevent carbid from falling from the cylinder when the cylinder is stationary.

To rotate the feed-cylinder at intervals, as required to cause carbid to drop into the generator D, automatic mechanism is connected with the bell A², the generator D, and the rotatable feed-cylinder D⁴, as follows: A rod g, having a semicircular lateral bend g', is fixed to the bearing or bracket B⁵ at its top end 85 and connected at its lower end with the perpendicular pipe B⁴ by means of a guide g'', fixed to the rod and slidably connected with said pipe in such a manner that the rod will move up and down with the bell. A rock-shaft h is mounted in bearings fixed to the outside and top portion of the generator D. An arm h' projects from the outer end of said shaft and is connected with the rod g by means of a ring or loop h'', swiveled to the 95 end of the arm, that allows the rod to move up and down relative to said arm and rock-shaft. A rotatable shaft J is mounted in a bearing J², fixed to the inside of the generator D and connected with the rock-shaft h by 100

means of a gear-wheel J^3 , fixed to the rotatable shaft in such a manner that intermittent rotary motion will be imparted to the rotatable shaft by the action of the rock-shaft 5 and such rotary motion transmitted to the feed-cylinder D^4 by means of a rotatable shaft k , journaled to the lower end of the bearer J^2 and fixed to the lower end of the feed-cylinder by means of a semicircular frame k' , a 10 bevel-gear on the shaft J , and a smaller miter-gear k'' on the shaft k , as required to cause carbide to drop from the cylinder into the water in the generator whenever necessary.

L represents a cover fitted and fastened to 15 the top and outside of the generator D in any suitable way, as required to conceal and protect the gear J^3 and J^4 and operative mechanism connected therewith.

When the bell A^2 and rod g descend, the 20 lateral bend g' imparts motion to the arm h' , as required to actuate the mechanism that transmits power and motion from the rod g to the feed-cylinder D^4 . A ratchet-wheel m , on the side face of the wheel J^3 , and a pawl m' , 25 connected with the arm h'' , lock the wheel J^3 to the shaft h , as required to rotate it and to transmit motion to the feed-cylinder at each descent of the bell and rod, and at each upward motion of the bell and rod the arm h' 30 resumes its normal position, while the wheel J^3 and shaft h remain stationary. It is therefore obvious that when the gas in the gas-holder has been reduced so as to allow the bell to descend the automatic feed mechanism will be actuated as required to generate a new supply of gas in the generator, to be 35 conveyed into the bell by means of the pipes B^3 and B^2 . Collars or stops m'' on the pipe A^4 and the rod or pipe B^4 restrict the upward 40 motion of the bell.

n represents a stuffing-box.

A sleeve n' , having a screen at its bottom and closed at its top, is placed on top of the pipe B^2 and floats n'' , connected therewith, 45 for filtering the gas and preventing gas from returning to the generator.

A screen P is fixed in the generator D to receive carbide as it falls from the feed-cylinder and to aid in subjecting the carbide to the 50 action of the water and to prevent accumulation of carbide in the bottom of the generator.

P^2 is a pipe connected with the bottom of the generator, and P^3 is an extension connected therewith by means of a swivel P^4 in such a manner that the extension can be turned down for removing residuum from the bottom of the generator.

R is a half-round stand-pipe fixed to the 60 outside of the generator D , and R^2 is an opening in the generator that communicates with the stand-pipe.

R^3 is a float fitted in the conveyer R , and R^4 is a stem that extends up from the float 65 through a guide R^5 , fixed to the outside of the magazine D^2 in such a manner that it will serve, in combination with indices s and s'

on the outside of the magazine, as an automatic register of the water-line in the generator. Pressure of gas upon the water will 70 cause the water and float to rise some space above the surface of the water in the generator, as shown.

A weight T on the end of an arm or bar T^2 , fixed to the shaft K , will when elevated by 75 the rotation of the shaft K as the bell descends fall back and in so doing continue the rotation of said shaft at a greater speed, and the feed-cylinder is by the force of gravity of the weight moved suddenly, and consequently 80 a greater quantity of carbide discharged therefrom to produce sufficient gas to cause the bell to ascend again. Positive action is thus 85 imparted to the rotatable feed-cylinder every time the quantity of gas in the bell is reduced sufficiently to cause the bell to descend and by means of the lateral bend g' in the rod g , carried by the bell, to actuate the feed mechanism in such a manner that no attendant 90 is required for feeding carbide to the generator as long as the supply in the magazine is not exhausted.

Having thus described the construction, functions, and arrangement and combination of all the parts, the practical operation and 95 utility of my invention will be readily understood by persons familiar with the art to which it pertains, and

What I claim as new, and desire to secure by Letters Patent, is—

1. In a gas-generator, the combination of a magazine adapted to retain carbide, a rotatable cylinder provided with interior pockets at the bottom of the magazine and a generator adapted to retain water and gas, for the 105 purposes stated.

2. In a gas-generator, a generator adapted to retain water and gas, a magazine adapted to retain carbide, a feed-cylinder provided with interior pockets adapted to carry carbide 110 rotatably connected with the lower end of the magazine, and means for operating the feed-cylinder, arranged and combined for the purposes stated.

3. In a gas-generator, a vessel or generator 115 adapted to retain water and gas, a magazine adapted to contain carbide on top of the generator and having an elbow at its lower end and an open-ended cylinder provided with pockets in its interior rotatably connected 120 with the end of said elbow, arranged and combined to operate in the manner set forth for the purposes stated.

4. In a gas-generator, a vessel or generator adapted to retain water and gas, a magazine 125 adapted to retain carbide on top of the retort and having an elbow at its lower end and an open-ended cylinder having pockets in its interior rotatably connected with the end of said elbow, a rotatable shaft fixed to the end 130 of the cylinder in alignment with the axis of the cylinder, arranged and combined to operate in the manner set forth for the purposes stated.

5. In a gas-generator, a vessel or generator adapted to retain water and gas, a magazine adapted to retain carbid and provided with an elbow-shaped and downwardly-inclined discharge-spout at its bottom, an open-ended feed-cylinder rotatably connected with the end of said spout and provided with transverse partitions to produce pockets, means for rotating the cylinder and a screen fixed in the 5 retort below the open end of the rotatable cylinder, arranged and combined to operate in the manner set forth for the purposes stated.
6. In an acetylene-gas apparatus, a generator adapted to retain water and gas, means 10 for feeding carbid into the retort, a stand-pipe fixed to the outside of the generator and communicating therewith at its lower end, a float fitted in said stand-pipe, a stem fixed to the float and extended perpendicularly on the out- 15 side of the generator, indices on the magazine and means for guiding the stem, arranged and combined to operate in the manner set forth for the purposes stated.
7. In a gas-generator, a generator adapted 20 to retain water and gas, a magazine adapted to retain carbid fixed on top of the generator and indices on the outside of the magazine, a stand-pipe fixed to the outside of the magazine and communicating with the generator, a float fitted in said stand-pipe and provided 25 with a stem extended upward to coact with the indices on the magazine, arranged and combined to operate in the manner set forth for the purposes stated.
- 30 8. In a gas-generator, a bell in a gas-holder, a rod having a lateral bend fixed to the bell, a generator adapted to retain water and gas, a magazine adapted to retain carbid on top of the generator, a rotatable feed-cylinder connected with the bottom of the magazine and 35 provided with interior pockets, a rotatable shaft fixed to said cylinder, a rotatable shaft in bearings fixed to the generator, a miter-gear on the inner end of said shaft and inside of the generator, and meshing with a bevel-gear 40 on the shaft fixed to the rotatable feed-cylinder, a rotatable shaft in bearings fixed to the outside of the generator, a gear-wheel loosely mounted on said shaft and meshing with a pinion on the outer end of the rotatable shaft 45 in a lower parallel plane, a ratchet-wheel fixed to said wheel on the upper shaft, a pawl pivotally connected with said shaft to engage said ratchet-wheel, an arm extending from the outer end of said shaft, a ring or loop 50 swiveled to the end of said arm and slidably connected with the rod fixed to and carried by the bell, all arranged and combined to operate in the manner set forth for the purposes stated.
9. In a gas-generator, a generator adapted to retain water and gas, a magazine adapted to retain carbid fixed on top of the generator, a rotatable feed-cylinder connected with the magazine and provided with interior trans- 55 verse partitions to produce pockets, means for rotating the cylinder and a weight connected with the cylinder, arranged and combined to operate in the manner set forth for the purposes stated.
10. In an acetylene-gas apparatus, the combination of a generator, a rotary carbid-feed barrel mounted in said generator and provided with partitions subdividing said barrel into pockets, and means for operating said feed-barrel.
